UNITED STATES PATENT OFFICE.

ORRIN C. DOW, OF ORANGE, MASSACHUSETTS.

MAINSPRING-WINDER.

SPECIFICATION forming part of Letters Patent No. 335,023, dated January 26, 1886.

Application filed September 19, 1885. Serial No. 177,600. (No model.)

To all whom it may concern:

Be it known that I, ORRIN C. Dow, of Orange, in the county of Franklin and State of Massachusetts, have invented certain new and useful Improvements in Jewelers' Tools; and I do hereby declare the following to be a full, clear, and exact description of the invention, such as will enable others skilled in the art to which it pertains to make and use it, reference being had to the accompanying drawings, which form part of this specification.

My invention relates to an improvement in jewelers' tools, and which is intended for coiling watch-springs and forcing them into the barrels; and it consists in the combination of the head or frame, which is provided with a socket at one end, with a shaft provided with a pin at one end, to attach it to the spring, and with a crank at the other, a sliding head provided with a sleeve which is screw-threaded at its inner end, and a nut which turns freely upon the shaft and operates the head, all of which will be more fully described hereinafter.

The object of my invention is to produce a tool for the use of jewelers, by means of which watch-springs of different lengths and widths may be coiled and then forced into barrels of different sizes.

Figure 1 is a vertical section of a tool embodying my invention. Fig. 2 is an edge view of the same.

A represents the frame or head, which has a horizontal opening made through its top, and which has the socket B screwed into one end. Passing horizontally through the opening made in the upper end of this head or frame is the shaft C, which has a pin, D, attached to one end, for the purpose of connecting the end of the spring to it, and a crank or handle, G, secured to the opposite end, for the purpose of revolving the shaft and coiling the watch-spring upon it. Upon the end of this shaft, next to the handle, is placed the nut H, which forms a part of the sleeve, which is provided with the flange I, behind which the set-screw J catches, and with the screw-thread L. The nut H is made large enough to be readily operated by hand, and has its outer surface milled, so that it can be readily held between the fingers. The sleeve of which this nut forms

a part is held in position upon the shaft by a shoulder at one end and by the handle or crank at the other.

The shaft and all of its attachments are held in position in the frame A by means of the set-screw J, which catches behind the flange I, and thus prevents the shaft from having any endwise movement, so that it can become displaced, but at the same time allows the nut and the sleeve, of which it forms a part, to revolve freely upon the shaft.

Passing through the opening which is made in the top of the frame A is a sleeve or collar, O, which has an internal screw-thread at its inner end, to engage with the screw-thread L. At the outer end of this collar is formed a head, P, which fits within the socket formed at one end of the head, as shown, and which head is moved back and forth by means of the nut and its sleeve, so as to force off into the barrels the springs which have been coiled around the end of the shaft. A number of openings or recesses, Q, are formed in the sides of the socket, and the head is so shaped that its outer edges catch in these recesses, and thus prevent the head from having any revolving movement whatever as the collar is being forced back and forth by the nut for the purpose of forcing the spring into the barrel. The end of the spring is passed through one of the openings in side of the socket, and has its end fastened to the pin D on the end of the shaft. When the shaft is made to revolve by means of a crank, the spring is coiled upon the shaft and within the socket B. Then the barrel is applied over the socket and the nut is turned toward the left, and thus the head is moved outward, so as to force the spring directly into the barrel. In order to enable the springs to be placed into different-sized barrels, different-sized heads or sockets will be used upon the same frame, A. Each socket will be formed as here shown and provided with recesses in its sides, so that the projections on the heads can freely pass through them. The same head will be used in connection with all of the different-sized sockets. Where springs of different widths have to be coiled, the head will be forced far enough outward in the socket to adjust it to the width of

the spring as it is being coiled upon the end of the shaft.

Having thus described my invention, I claim—

- 5 1. The frame A, provided with a socket upon one end and an endwise-moving head inside of the socket, and the shaft upon which the spring is to be wound, substantially as shown.
- 10 2. The combination of the frame, a shaft which passes through it, a socket on one end of the frame having a recess or recesses, and an endwise-moving head which has projections to pass through the recesses in the head, substantially as described.
- 15 3. The combination of the frame, the shaft passing through it, the socket on one end of

the frame, the endwise-moving head provided with a sleeve, and a nut for moving the sleeve and head endwise, substantially as set forth. 20

4. The combination of the frame, the shaft provided with a crank at one end and a pin at the other, a nut which is swiveled upon the shaft, the set-screw for preventing the nut and the shaft from being removed from the frame, 25 and the head and sleeve made in a single piece, substantially as specified.

In testimony whereof I affix my signature in presence of two witnesses.

ORRIN C. DOW.
